(57) CLAIM

The ornamental design for a garden hose support, as shown and described.

DESCRIPTION

FIG. 1 is a front perspective view of a garden hose support, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the garden hose support in an environment of use.

The broken lines in the drawings illustrate the portions of the garden hose support, which form no part of the claimed design.
